C. E. ILES

ADDITION TO SEWING THIMBLES

Filed March 7, 1925

Inventor
Charles Edward Iles,
by Attorney.

Patented Feb. 16, 1926.

1,573,715

UNITED STATES PATENT OFFICE.

CHARLES EDWARD ILES, OF BIRMINGHAM, ENGLAND, ASSIGNOR OF ONE-FOURTH TO FREDERICK HENRY AMSDEN, ONE-FOURTH TO LLEWELLYN CHARLES HOY, BOTH OF LONDON, ENGLAND, AND ONE-FOURTH TO THOMAS FREDERICK THIRLBY, OF BIRMINGHAM, ENGLAND; EMILY ANNE ILES AND CHARLES EDWARD ILES EXECUTORS OF SAID CHARLES EDWARD ILES, DECEASED.

ADDITION TO SEWING THIMBLES.

Application filed March 7, 1925. Serial No. 13,875.

To all whom it may concern:

Be it known that I, CHARLES EDWARD ILES, subject of the King of Great Britain, residing at Birmingham, England, have invented 5 an Improvement in or Addition to Sewing Thimbles, of which the following is a specification.

This invention relates to sewing thimbles of that type which are combined with needle-threaders, and the invention consists essentially in the provision of a needle-threader which is pivoted or otherwise connected to the thimble in such a manner that it may be turned or moved into a protected 10 position when not required for use. For this purpose the needle-threader, which may be of a hook formation or gapped or forked, may be pivoted to the side of the thimble near its edge, so that it may be turned about 15 the pivot to project from the said edge when required for use, whilst when not required it may be turned to lie against the wall or side of the thimble, out of the way, the said wall being preferably formed with the flat- 20 tened portion against which the needle-threader may then engage. The pivot about which the needle-threader turns may be constituted by a screw, so that the needle-threader may be readily detached and a 25 fresh one substituted should breakage occur; or it may be detachably held in engagement with a projection or pivot upon the thimble by a blade spring. If desired, however, 30 other means may be employed for rendering the needle-threader readily detachable and which permits of the thimble being turned or moved into a protected position when not required.

Figure 1 of the accompanying drawings 40 is a perspective view of a combined thimble and needle-threader constructed in accordance with this invention, showing the thimble in use.

Figure 2 is a perspective view showing the 45 needle-threader in its protected out-of-use position.

Figure 3 is a horizontal section through the thimble on line 3—3, Figure 2, upon a larger scale, showing the method of pivoting 50 the needle-threader.

Figures 4 and 5 are horizontal sections showing further methods of pivoting the needle-threader.

Figure 6 is a section showing how the needle-threader may be attached by a rivet. 55

Figure 7 is a side elevation, and

Figure 8 is a horizontal section on line 8—8, Figure 7, showing another method of detachably mounting the needle-threader on the thimble. 60

Figure 9 shows a modified form of needle-threader combined with the thimble.

Referring to Figures 1 to 3, the thimble *a* has combined with it a needle-threader *b*. The needle-threader is in the form of a flat 65 blade having a narrow hook-shaped outer end which is adapted to be inserted through the eye of a needle in order to draw the cotton or thread through the same, as shown in Figure 1. The inner end of the needle-threader is wider and is pierced with a small hole adapted to be engaged over a short outstanding boss or projection *c* (Figure 3) carried by the base portion of the thimble near its edge, and preferably 70 stamped up from or formed integral with the said base portion. This outstanding boss or projection *c* is adapted to serve as a pivot about which the needle-threader *b* may be turned, and is formed with an internally- 75 threaded axial hole adapted to receive a screw *d*. This screw serves to retain the needle-threader in place upon the boss or projection *c* and is formed for this purpose with a head adapted to come above the 80 needle-threader and prevent its removal. The said boss or projection *c* gives an extended bearing for the screw and also prevents the head of the latter from binding upon the needle-threader and thereby preventing it from freely turning about the boss as a pivot. When the needle-threader *b* is required for use it is turned about the boss *c* so that its hooked end projects beyond the edge of the base of the thimble, as in 85 Figure 1, whilst when it is not required it is turned so as to lie against the outer face or wall of the thimble, as in Figure 2, the thimble being formed with a flattened portion *e* with which the needle-threader is 90

then arranged to engage, so that it thus lies out of the way close to the thimble and does not interfere with the use of the latter for sewing. Should the needle-threader break it may be readily removed from the boss or projection upon which it is mounted by removing the screw, and a fresh needle-threader may be easily fitted in its place, the screw being again engaged with the hole 10 in the boss to secure the needle-threader in position.

As shown in Figure 4, instead of a boss being stamped up from the thimble *a* to receive the screw *d*, the latter may engage a 15 tapped hole in the wall of the thimble and may pass through a washer *f* arranged to fit within an enlarged hole in the end of the needle-threader *b*, the said washer being adapted to project slightly above the needle-threader and thereby prevent the head of the screw from binding against the latter.

Or, as shown in Figure 5, a shouldered screw *d* may be employed, having a plain reduced part or collar *d*¹ about which the 20 needle-threader *b* may turn. Where the needle-threader *b* is not required to be detachable, it may be pivoted to the thimble *a* by means of a rivet *g*, as shown in Figure 6, the head of the rivet engaging a washer *h*.

As shown in Figures 7 and 8, instead of the needle-threader being detachably secured to the thimble *a* by a screw, a spring *j* may be used. In this arrangement a hole in the inner end of the needle-threader *b* is engaged with a short outwardly-projecting pin or stud *k* attached to or stamped up from the thimble, preferably near the edge of its base portion. The needle-threader *b* is adapted to be freely turned about this pin or stud, 40 which serves as a pivot, and is held in place thereon by means of the blade spring *j*. The one end of this spring is arranged to bear upon the needle-threader *b* and is provided with a hole which fits over the said pin, 45 whilst its opposite end is pivoted at *m* to the base portion of the thimble by a rivet, so that it normally lies alongside the edge of the said base portion. The spring thus serves to hold the threader upon the pin, 50 and by slightly raising the spring and swinging it aside about its pivoted end, the needle-threader may be readily detached. A fresh needle-threader may then be fitted in its place when necessary. The retaining

spring *j* is curved longitudinally and is preferably formed at about its middle with a transverse rib or corrugation *j*¹ which ensures the free end of the spring bearing firmly upon the needle-threader. The thimble is preferably formed with a flattened portion *e*, as in the previously described arrangement, against which the needle-threader engages when turned into its out-of-use position, as shown by dotted lines in Figure 7, although this flattened portion may be dispensed with in either arrangement, if desired; or the thimble may be formed with a recess to receive the needle-threader when turned into its out-of-use position.

Any other suitable means may be provided for pivoting or connecting the needle-threader to the thimble so that it may be turned or moved into a protected position when not required for use. The needle-threader *b* may be of any other suitable construction than that shown in Figures 1 to 8; it may, for example, as shown in Figure 9, have a forked or recessed end *b*¹ instead of a hooked end, so as to push the cotton through the eye of the needle.

Having fully described my invention, what I desire to claim and secure by Letters Patent is:—

1. A thimble having a part of its outer side constructed to lie below the general contour of the outer surface, and a needle threader of thin material pivotally connected adjacent the open end of the thimble and movable to engage with the part of the outer side of the thimble which lies below the general contour of the surface thereof to protect the threader when not in use and also cause it to lie close to the outer side of the thimble.

2. A thimble having its outer side formed with a flattened portion, and a needle threader pivoted adjacent to the open end of the thimble and rotatable for engagement with the said flattened part when not in use.

3. A thimble having a flattened part on its outer side, and a needle threader having a hooked end pivotally attached to the thimble near the open end thereof and movable into engagement with said flattened part when not required for use.

In testimony whereof I have hereunto set my hand.

CHARLES EDWARD ILES.
